UNITED STATES PATENT OFFICE.

CHRISTIAN JOHN JENNE, OF SAN FRANCISCO, CALIFORNIA.

ELECTRIC-ALARM SYSTEM.

1,375,516.

Specification of Letters Patent. Patented Apr. 19, 1921.

Application filed November 2, 1916. Serial No. 129,122.

To all whom it may concern:

Be it known that I, CHRISTIAN J. JENNE, a citizen of the United States, and a resident of San Francisco, in the county of San Francisco and State of California, have invented a new and useful Improvement in Electric-Alarm Systems, of which the following is a specification.

My invention relates to an electrically operated automatic fire, burglar and police alarm system, and it consists in the combinations, constructions and arrangements hereinafter described and claimed.

The apparatus includes a central station equipment, equipments at the various subscribers' stations and lines connecting the central station with the subscriber's station.

An object of the present invention is to provide a system of the type mentioned in which a relatively large number of stations may be operated on one circuit, this being due to the fact that each station has a shunt magnet operated only in case the protection circuit is opened as will be explained later.

Another object of the invention is to provide a balancing resistance which will enable the subscriber to open and close his private lines at will while not altering the resistance of his premises as a unit, a cut-out switch bar being provided for this purpose.

A further object of my invention is to provide a system by means of which the balancing of the line may be ascertained at the central office or station by bridge tests.

A further object of my invention is to save line wire from the central office or station to the different places to be protected.

Other objects and advantages will appear in the following specification and the novel features of the invention will be particularly pointed out in the appended claims.

My invention is illustrated in the accompanying drawings forming part of this application, and in which,

Figure 1 is a diagrammatic view showing the central station equipment and the circuits leading therefrom,

Fig. 2 is a diagrammatic view showing a subscriber's station with a plurality of rooms and equipment for protecting the same,

Fig. 3 shows a sectional view of a door lock with the cut-out used therewith,

Fig. 4 is a face view of the door cut-out,

Fig. 5 is a plan view of one of the fire signal fuses,

Fig. 6 is a view in side elevation and in section of the magnet cut-out,

Fig. 7 is a section of a portion of the magnet cut out,

Fig. 8 is an end view of the subscriber's cut-out switch, and

Fig. 9 is a side view of the resistance balancing coil.

Fig. 10 is a front view on full size of the subscriber's control apparatus shown diagrammatically in Fig. 2.

Fig. 11 is an edge view looking down, of the subscriber's control board, and

Fig. 12 is a sectional view looking from the right on the line 12-12, Fig. 10.

In carrying out my invention I provide a central station having the equipment illustrated in Fig. 1. This includes a register 2, a gong 3, relays 4^a, 4^b and 4^c, a galvanometer 5, the adjustable resistances 6, 7 and 8 respectively, the batteries B and B', the variable resistances 9^a, 9^b and 9^c respectively, the spring jacks 10^a, 10^b and 10^c and the fuses 11. A plug P is arranged to be connected with any of the jacks 10^a, 10^b and 10^c for the purpose of testing the line in the manner hereinafter described. Any suitable control, testing alarm and motive apparatus may be used in the central station, the station shown being merely illustrative.

In order to make the testing of the line easier, the entire set of lines 12^a, 12^b and 12^c are made up to the same total resistance with the variable resistances 9^a, 9^b and 9^c.

The central station wiring may be of any desired form for the purpose of enabling the operator to receive a signal and to test the line resistance at any time. The battery has a wire g extending to the ground G and to the resistance 8 from which resistance a wire 8' extends to the resistance 7, a wire 7' extending to the galvanometer 5. From the other binding post of the galvanometer a wire 5' connects with the jack wire 6' which wire is also connected to the resistance 6. The resistances 6 and 7 are connected by the wire 6'' and p indicates the other wire leading from the wire 6'' to the plug P.

The alarm bell B² is provided with wires B³, B⁴, B⁵ and B⁶ which are connected to the battery B' and the arrangement of the galvanometer is such that if its needle moves more than a predetermined amount that the bell will ring. In testing it will be

5 noted that the resistances 6, 7 and 8 are arranged so that with 6 and 7 on one side of the galvanometer and 8 and the subscriber's lines on the other side, a balanced

5 Wheatstone bridge is produced and the galvanometer needle will stand at zero if the lines are intact.

From the battery B a wire c extends to and is connected with the wires c' and c'', 10 all three being connected to separate fuses 11. The fuses 11 are connected to the resistances 9^a, 9^b and 9^c by the wires e, d-e', d'- and e'', d'', and said resistances are connected to the relays 4^a, 4^b, and 4^c by the 15 wires f, f', f'', and the final subscriber has a ground wire g'. The relays are for the purpose of allowing the subscribers to send in individual signals over the local wires L, L' and 2' to the gong and register. However, 20 the type of central office is not material to the invention, any such apparatus as will enable the line to be tested and the signal to be received being usable.

In Fig. 2 I have shown two stations which 25 are to be protected in the same block. In order to fully understand the working of the system, I am describing in detail the equipment of each station. Each subscriber is provided with a day call box 13 of any 30 well known pattern, which call box sends the same signal as the breaker wheel 14 of this apparatus. This apparatus is mounted upon a base 15 which has four binding posts 16, 17, 18 and 19 at one end thereof and it 35 has a suitable case 20 containing the mechanism for driving the breaker wheel 14, including a spring drum 21, said spring drum having a projecting pin 22 for a purpose to be later explained.

40 On the top of the casing 20 there is a fiber block 23 which has contact springs 24, 25 on its sides, the latter spring having its end in position to be engaged by the toothed breaker wheel when it rotates. At one end 45 of the plate 15 there is a double pole electromagnet 26 which has a pivoted armature 27 held normally away therefrom by means of a spring 28 connected to the armature and to a post 29. A double headed screw 30 50 confines the armature so that it cannot move more than a given amount when the magnets are energized. Extending over the magnet frame and connected with the armature is a finger 31 which finger is in alignment with the mark adjacent the letters O. K. at 32 when the magnets are not energized, which letters are for the purpose of enabling the subscriber to know that his local line is in proper condition to be left 55 for the night. Between the casing 20 and magnets 26 there is a bar 34 which is pivoted to a post 35 and which bar is for the purpose of short circuiting the magnets out of circuit when a call has been sent in.

60 The bar 34 carries a small fiber roller 36

and a fiber block 37 to which a metallic contact point 38 is secured. See Fig. 7. The fiber block 37 moves between two springs 39, 40 which are secured to the base 15 and to which springs the cut-out wires 70, 71 70 are connected. A spring 41 carried by a post 42 is used to support the bar 34 when set and a spring 43 tends to pull the bar 34 and point 38 down to short circuit the magnets when the pin 22 contacts with said 75 spring 41 when an alarm has been sent in.

On the base 15 there is the subscriber's cut-out switch bar 44 which passes under a cleat 45 adapted to hold it down so that the spring 46 carried by the said switch bar 80 will make a good contact with the contact blocks 47, 48, and will pass from one to the other without opening the line. This switch lever has a roller 49 at the end thereof at the end of which roller there is a fixed 85 spring 50 bearing thereon to compel the switch lever to remain either in the position indicated in Fig. 2 or fully over on the contact plate 47, as the case may be. The switch lever has a bar 51 pivoted thereto 90 which passes under a cleat 52 and which carries a projecting lug 53, said lug being adapted to pass under the roller 36 to reset the bar 34.

The armature 27 has a bar 54 rigidly connected therewith which is pivoted on a pin 55 carried by a bracket 56 adjacent the opposite end of the base 15. The bar 54 has a trip lever 57 rigidly connected therewith which is adapted to release the clock train 100 when the armature 27 is moved by the magnets being energized.

Adjacent the binding posts 16 to 19 inclusive are other binding posts 58, 59 between which there is a fiber rod 60 with a 105 resistance wire around it as indicated at 64'. The fiber rod 60 has metallic caps at 61, 62 at its ends which are adapted to make an electrical contact with the spring clips 63', 64 which are electrically connected to the 110 binding posts 58, 59. A clamp 63 surrounds the fiber rod 60 and the resistance wire 64' carried by said rod, while a short flexible cable connects said clamp with the binding post 59 to complete one of the electrical circuits. 115

The wiring system is as follows: The main lead wire 12^a is connected to the binding post 16 while the other main lead wires 12^b and 12^c lead to other protected blocks. 120 A wire 16^x is connected to one of the binding posts of the day call box 13, from the other binding post of which a wire 66 extends to the binding post 19, a wire 67 connecting the latter binding post with the binding post 18. From the binding post 18 a wire 68 extends to one pole of the magnet 26, while from the other pole thereof a wire 69 extends to the binding post 17. The magnet also has wires 70, 71 connected there- 125 130

with and with the two contact springs 39, 40, the object being to cut out the magnet when the contact point 38 connects the two springs 39, 40. From the binding post 16 5 a wire 72 extends to the binding post 59 and from there a wire 73 extends to the contact spring 24. From the contact spring 25 a wire 74 extends to the contact plate 48.

From the pivoted end of the switch bar 10 44 a wire 75 extends to the binding post 17. From the contact plate 47 a wire 76 extends to the binding post 58, which latter is electrically connected with the binding post 59 by means of the resistance wire 64' and 15 cable 65 previously mentioned. From the binding post 17 a wire 77 extends out to the premises to be protected and back to the binding post 18. The said wire 77 passes around the front door 78 around the building 20 and has suitable burglar alarm devices of any desirable type at 79, said burglar alarm devices forming no part of the present invention. In its course around the building the wire 77 may extend as often 25 as may be desired to the porcelain blocks 80, two of such blocks being shown in the present instance, although the number may be more or less. These porcelain blocks carry springs 81, 82 which are electrically 30 connected to the local wire 77 and which are electrically connected to each other by means of the fusible link 83, said link being of such a material as to melt at a temperature of from 150 to 200 degrees, thereby breaking 35 the electric circuit between the springs 81, 82.

The course of the electric current from the battery B under normal conditions is through the wire c, to fuse 11, wire d to contacts 10^a, wire e to resistance 9^a, wire f to contact block 4^a and connection with wire 40 12^a which is connected with the binding post 16 on the subscriber's base plate 15. From the post 16, the current will travel via the wires 72 and 73 to the contacts 24, 45 25 to wire 74, to switch 44, wire 75 and binding post 17. From the binding post 17 the current will divide and pass via wire 69, magnets 26 and wire 68 to binding post 18, the other portion of the current passing 50 around the building through the wire 77 back to the binding post 18. From the binding post 18 the current will pass via wire 67 to binding post 19, then by wire 66 to call box 13 to wire 16^a connected with 55 a wire corresponding to 12^a in the next premises, and after leaving the last subscriber's premises will pass through the wire g' to the ground. The other side of the battery is grounded by the wire g where- 60 by the circuit is completed.

Each line wire 12^a, 12^b and 12^c is similarly connected up with different series of subscribers.

When the protection circuit has been 65 broken at a door or window all of the

current will be thrown on the magnets 26 with the result that the clock train will be released and the pin 22 will strike the latch 41 and drop the arm 34 whereupon the house circuit will pass from 70 the binding post 17 to the binding post 18 via wires 69, 70, contacts 39, 40, and wires 71, 68, both the protection circuit and the magnets being then cut out, but as a signal is in process of being sent in the change in 75 line resistance is a matter of no moment.

In order to enable the subscriber or other person authorized to enter the building a front door is provided with a lock 84 having a slidable bolt 85 which slidable bolt engages 80 a fiber block 86 carrying a metallic point 87, said metallic point being adapted to electrically connect the two contact plates 88, 89 when the door has been opened with a suitable key. The contact point 87 is pushed 85 into engagement with the two plates 88, 89 when the bolt is withdrawn, by means of a suitable spring 90.

Wires 91, 92 are connected to the wire 77 so that when the front door is opened by 90 having the lock opened, the front door will be cut out of circuit thereby enabling the owner of the store or office to go into the building without sending in an alarm.

In the installation of the apparatus the 95 resistance wire 64' from the binding post 58 to the binding post 59 is arranged by shifting the clamp 63 to precisely equal the resistance of the wire used throughout the protected building, the object being to maintain 100 the line at all times save when the owner opens the front door at the same resistance, thereby enabling the central office to know that the line has not been tampered with by unauthorized persons. The reduction in line 105 resistance due to opening the front door is so small that it will not affect the line. The subscriber then shifts his lever 44 thereby shifting the line resistance from his premises to the resistance wire 64', which resistance 110 wire has been at the installation of the apparatus set to equal the resistance of the premises and as this time is usually short no changed line condition will be apparent at the central office for a long enough time to 115 indicate that the line needs investigation.

When the switch lever 44 is shifted from 48 to 49 by the proprietor, the house circuit will then be from the binding post 16 via wires 72 and 65 to a portion of the resistance 120 wire 64' equal to the protection circuit, then through wires h and 76 to bar 44, thence via the wire 75 to post 17. If the protection circuit is broken, the arm 34 will be dropped and the magnets will be shunted, but no signal 125 will be sent since there is no contact with the wire 74. If the protection circuit is not broken, the circuits will remain as first explained. The circuits external to the protected premises will always remain the same 130

except when testing as will be further explained.

When the subscriber is ready to lock up at night he will go around and close all of his doors and windows including his front door and will throw the bolt in it, whereupon he will shift the lever 44. If his line is intact the pointer 31 will remain at the O. K. position. He can then go and unlock his front door and pass out and lock it knowing that the premises will be adequately protected.

On the other hand if when he shifts his lever 44 the clock train starts to move he must at once shift the lever 44 back to the contact 47.

15 This will prevent the signal from being sent and as soon as the pin 22 travels around once, the clock train will be stopped by the bar 57. The signal cannot be sent at this time since contacts 24, 25 are then out of circuit and when the clock train starts, it is several seconds before the breaker wheel touches the spring 25. The subscriber can then go around his premises and ascertain the cause of the trouble with his local circuit. If it is due to a window being open he can close that, or if he cannot ascertain the trouble he can shift his lever 44 to the contact 48 and permit an alarm to be sent in, whereupon an investigation of his premises 30 will be made.

The circuits of all the subscribers in one block are made in series with the exception that the magnets 26 in each subscriber's premises are shunted with respect to the wires extending around the subscriber's premises, so that said magnets are not energized by the current traveling to a sufficient extent to draw up their armatures unless the local circuit wire 77 is broken at some point 35 and as soon as the break is made and the signal sent the magnet will be cut out of circuit thereby reducing the total line resistance by one subscriber, but inasmuch as an alarm has been sent in at this time proper 40 arrangements at the central office can be made to ascertain the proper line resistance 45 under such conditions.

Should a fire occur in any subscriber's store one of the fusible links 83 will be melted and will at once break the subscriber's local circuit, sending in an alarm in precisely the same way as the alarm is sent in by the breaking of the circuit at one of the windows or doors.

50 It is to be observed that when the subscriber pushes his lever 44 to the left, Fig. 2, that at the same time it raises the arm 34 and allows the spring 41 to hold it up, whereupon the local circuit and magnet circuit will be in parallel again, but inasmuch as the magnet circuit is of much greater resistance than the local circuit, said magnets will not be energized. When the switch lever 44 is moved to the right, Fig. 2, so 55 much of the resistance wire 64' as is re-

quired to balance the local circuit will be in series with the magnets 26 and protection circuit which two latter are in parallel. Thereupon the current will still flow through the protection circuit and through the magnets 26, but shortly after the switch lever 44 has been thrown to the contact 47, the protection circuit will be opened at some point by the subscriber and the magnets 26 will be energized, thereby cutting themselves 70 out of circuit and leaving the subscriber's resistance 64' in circuit alone to the line. This change is ordinarily made shortly after the lever 44 is shifted so that the line 80 is not disturbed by the addition of the resistance 64' for a long enough time to be serious. When the local protection circuit is open, a signal may be sent from the day call box 13.

At the central station I have shown lines 85 12^a, 12^b and 12^c which extend to separate blocks. Each of these blocks is on a separate circuit and the subscribers' sub-stations of any particular block are arranged in series. The arrangement is such that the 90 resistance which is brought into the circuit as described is equal to that of the loop which it replaces so that there is a balanced condition, which condition may be ascertained at the central station by inserting 95 the plug P in one of the jacks 10^a, 10^b and 10^c, and making a test by the Wheatstone's bridge set.

By this means the central office can determine the condition of any circuit at all 100 times. The best of these circuits is made periodically by the attendant at the central station and thus the condition of the whole system may be accurately determined at all 105 times.

Let us assume that the operator is to test a circuit of the set 12^a, ^b or ^c.

The resistances 9^a, ^b, and ^c are set to make the same total resistances in all the line circuits and the resistances at the galvanometer 110 are set so that the galvanometer needle will read zero when a resistance corresponding to the total resistance of one of the lines is placed across the plug P. The plug is then inserted in one of the spring jacks 10^a, ^b or ^c 115 and so long as the galvanometer needle reads within a few ohms of zero, the operator knows the circuits are in proper condition for the sending of a signal and the lines not tampered with. If the galvanometer needle reads over or under five ohms, that being a standard multiple used for the local circuits in the subscriber's premises, the attendant will send out several patrolmen 120 to investigate all the premises on the line 125 found to be at fault.

The central operator has keys for each protected place under seal, and after the seal is broken the patrolmen take out the keys to find out which place is causing the trouble, 130

after which the keys are returned to be resealed. In the event that the premises are so opened, the owner is advised of such entry.

5 I claim:

1. An alarm system comprising a central station having suitable registering and alarm apparatus, a plurality of subscribers' stations, each station having a closed loop around the building to be protected, the loops of the various stations being in series, electrical connections between the central station and the series of loops, means at each subscriber's station for transmitting its individual signal to the central station on the breaking of the loop at any point or the increase of resistance thereof, and manual means for shunting the loop when the latter is broken or the resistance thereof increased, to maintain the circuit connections with the other loops of the series at the original resistance.
- 10 2. An alarm system comprising a central station having suitable registering and alarm apparatus, a plurality of subscribers' stations, each station having a closed loop around the building to be protected, the loops of the various stations being in series, electrical connections between the central station and the series of loops, means at each subscriber's station for transmitting its individual signal to the central station on the breaking of the loop at any point or the increase of resistance thereof, and manual means for shunting the loop when the latter is broken or the resistance thereof increased, to maintain the circuit connections with the other loops of the series, the shunt around each loop having a resistance equal 15 to the resistance of the loop whereby the line is balanced at all times.
- 20 3. An alarm system comprising a central station having suitable registering and alarm apparatus, a plurality of subscribers' stations, each station having a loop around the building to be protected, the loops of the various stations being in series, electrical connections between the central station and the series of loops, means at each subscriber's station for transmitting its individual signal to the central station on the breaking of the loop at any point or the increase of resistance thereof, manual means for shunting the loop when the latter is 25 broken or the resistance thereof increased, to maintain the circuit connections with the other loops of the series, the shunt around each loop having a resistance equal to the resistance of the loop whereby the line is balanced at all times, and means at the central station for testing the balanced condition of the circuit.
- 30 4. An alarm system comprising a central station having suitable registering and alarm apparatus, a plurality of circuits ex-

tending from said central station, each of said circuits comprising a plurality of subscribers' stations, each station having a closed loop and the loops of the stations on any one circuit being arranged in series, a shunt around each loop having the same resistance as the loop, and manual means at each station for switching circuit to the shunt on the breaking of the loop whereby the balance of the entire circuit is maintained.

5. An alarm system comprising a central station having suitable registering and alarm apparatus, a plurality of circuits extending from said central station, each of said circuits comprising a plurality of subscribers' stations, each station having a closed loop and the loops of the stations on any one circuit being arranged in series, a shunt around each loop having the same resistance as the loop, manual means at each station for switching circuit to the shunt on the breaking of the loop whereby the balance of the entire circuit is maintained, and means at the central station for ascertaining the balanced condition of any of said circuits.

6. In a signal system a central receiving and testing station, a closed circuit extending therefrom, a closed house circuit, a magnet circuit in parallel with the latter circuit, both of said circuits forming a part of the central station circuit, signal sending means, means operated by said magnet when fully energized to start the signal sending means, means to thereupon cut the magnet out of circuit and means to balance the house circuit to leave the line at the original resistance.

7. An electric signal system comprising a central receiving and testing station, an electric circuit extending therefrom, a house circuit, a magnet in parallel with the house circuit and both the latter circuits forming a part of the circuit extending to the central station, signal sending means, means whereby the magnet starts the operation of the signal sending means upon changes in the house circuit, means to thereupon cut the magnet out of the circuit and manual means to insert a balancing resistance to leave the line at the original total resistance.

8. An electric signal system comprising a central receiving and testing station, an electric circuit extending therefrom, a plurality of closed house circuits, a magnet circuit in parallel with each of the house circuits all of which house and magnet circuits being in series with each other and forming a part of the circuit extending to the central station, a signal sending means at each house circuit, means whereby the magnets adjacent each house circuit will cause the sending of the signal when their adjacent house

125

130

6
circuit is interfered with and means to cut the magnet out of the circuit and to institute therefor a balancing resistance substantially equivalent to the resistance of the 5 house circuit when the latter is cut out.

9. An electric signal system comprising a central receiving and testing station, an electric circuit extending therefrom, a plurality of closed house circuits in series with 10 each other and with the former circuit, a

magnet in parallel with each individual house circuit, signal sending means adjacent each house circuit, means whereby the magnet causes the operation of the signal sending means when its adjacent house circuit is interfered with, means to thereupon cut the magnet out of the circuit and manual means to balance the house circuit to leave the line at the original resistance. 15

CHRISTIAN JOHN JENNE.
